UNITED STATES PATENT OFFICE

2,417,138

STOVE WITH INTERNAL AIR CHAMBER

August F. P. Stenzy, Baltimore, Md.

Application September 10, 1943, Serial No. 501,857

2 Claims. (Cl. 126—70)

1

This invention relates to a heating stove, and provides a construction wherein a materially increased number of heat units per size of stove and quantity of fuel is attained.

Further, I aim to attend the end in view by supplying a superheating or hot air chamber or pot at the top of a stove occupying most of the area thereof and which is adjustable toward and away from the firebed, and which may be equipped with any suitable heat outlet means.

The more specific objects and advantages will become apparent from a consideration of the description following taken in connection with accompanying drawings illustrating an operative embodiment.

In said drawings:

Figure 1 is a view in elevation of the improved stove;

Figure 2 is a vertical sectional view taken on the line 2—2 of Figure 1;

Figure 3 is a horizontal section taken on the plane of line 3—3 of Figure 2;

Figure 4 is a horizontal section taken on the plane of line 4—4 of Figure 2;

Figure 5 is a horizontal section taken on the line 5—5 of Figure 2;

Figure 6 is a plan view of a damper closure which may be used at the top of the superheating chamber or pot; and

Figure 7 is a vertical sectional view taken on the line 7—7 of Figure 6.

Referring specifically to the drawings wherein like reference characters designate like or similar parts, the stove disclosed has a suitable outer casing at 10 generally cylindrical in form and supported as by conventional legs 11. The fire box or base portion of the casing is lined with firebrick or any equivalent material at 12, at the base of which a grate 13 is provided, the same preferably being round as shown and mounted for rocking on trunnions 14 and 15, suitably journaled in the brick, the latter extending to the exterior of the casing through its wall and having a head 16 polygonal in cross-section for engagement by a crank or shaker. This grate, as best shown in Figure 4, consists of a plurality of relatively close bars 17 providing relatively narrow slots 18 between them. In addition lugs or upward projections 19 rise from the bars 17 at suitable intervals. As a result of this construction the grate is relatively flat and the lugs and narrow openings or slots 18 prevent the undue dropping of coal therethrough and its consequent waste.

Coal is supplied to the grate and fire box 55

2

through a conventional opening covered by a door 20 hinged to the casing 10.

To enable maximum air to enter the stove and issue beneath the fire grate 13, I provide an 5 arcuate space or channel 21 in the top of the wall 12 in communication with the outside atmosphere through one or more openings 22 in the casing, and lead downwardly from the channel 21 any suitable number of grooves or channels 23 which open below the grate 13 in the ash chamber or space 24, which may have a removal opening of conventional design covered by a conventional door 25 hinged to the casing 10.

An important part of my invention consists 15 in using the hot air chamber or pot 26 having a cylindrical side wall 27 as shown and a closed bottom wall 28. This pot is adapted for vertical adjustment relative to the fire bed, as it is supported in a central opening of a ring-like cover 29 mounted on the casing, and held in adjusted position in the opening of the ring by any suitable number of bolts 30 screwed on the ring and in bearing engagement with the pot. A pair of handles 31 may extend from the pot to facilitate 20 handling and adjustment thereof. Also, the pot is open at the top and may be closed by a cover 32 as shown in Figure 2, the same being removable and having an inwardly extending rim or flange 33 telescoped into the pot and centrally having a hot air pipe 34 leading therefrom to convey the heated air from the pot.

In lieu of the cover 32 and hot air pipe, I may employ an adjustable damper construction as disclosed in Figures 6 and 7. This construction 35 includes a relatively flat cover 35 having an outside flange 36 telescoped over the upper end of the pot and notched as at 37, so that it will clear the handles 31. Any suitable number of openings 38 for the emission of heat are provided 40 through cover 35 and they are controlled by a fan-shaped damper 39 pivotally connected by a stud 40, centrally of the cover 35, the stud enabling attachment of a crank or the like to a square head 41 thereof to turn it partially open, or to close the openings 38 by bringing blades 42 into partial or complete registry with the openings 38.

A circular generator 43 may surround the pot 27 adjacent the lower end, the same having a water-inlet pipe 44 leading through the wall of the casing 10 and also having an outlet pipe 45 leading through the wall 10, the latter being adapted to supply anti-freeze liquid to water within the generator 43.

A smoke-discharge flue is provided adjacent the

top of the casing 10 near ring 29 at 46, and it has a conventional adjustable damper 47 operatively mounted therein.

In actual use, for one example, the pot 21 may have an outside diameter of 14 inches. It will be realized that this covers most of the space at the top of the casing 10. This pot may be of metal, clay, cast iron, or any other equivalent material. It has been found by tests that with the use of this pot 26 four times the delivery of heat units is attained as with an ordinary construction of stove, using the same amount of ordinary egg-size coal. The superheated air may be efficiently directed to the house or rooms where desired, and the pot is adjustable to obtain maximum control. The circular cast iron generator 43 is cast in one piece with the proper inlets and outlets, and the anti-freeze liquid introduced through the pipe 45 will be vaporized and will reach the radiators as the hot water is generated for the hot water tank; this hot vapor and hot water generator may be of coil shape or water bag shape with a single or double compartment and be made of any kind of metal or other material. The structure gives effective control of the heat and enables the use and application of any accessories and controls. The same principles may be practiced regardless of the specific fuel used, that is, whether it be gas, electricity, wood, coal, etc.

The structure also enables the saving of fuel and of metal in its manufacture.

Various changes may be resorted to provided that they fall within the spirit and scope of the invention.

I claim as my invention:

1. A stove of the class described having a casing, a pot disposed in the upper portion thereof

and relatively large with respect to the casing, and means to heat said pot, a smoke-discharge flue leading from the casing at one side of the pot relatively close to the top of the casing, and a circular generator about the lower portion of the pot, said pot being adjustable in the casing relatively to its firepot and to the generator and flue.

2. A stove comprising a casing having a flanged opening in the top thereof, a pot extending into the casing, through said opening, and adjustable lengthwise of the firepot thereof, means carried by the flange for engaging the pot to retain the latter in various positions, said pot being spaced from the casing wall, and a circular generator located between the pot and casing wall and relative to which the pot is adjustable.

AUGUST F. P. STENZY.
